UNITED STATES PATENT OFFICE.

ALBERT AUMONT, OF MONTREAL, QUEBEC, CANADA.

BATHING-SHOE.

1,074,595.

Specification of Letters Patent.

Patented Oct. 7, 1913.

Application filed March 14, 1913. Serial No. 754,297.

To all whom it may concern:

Be it known that I, ALBERT AUMONT, a subject of the King of Great Britain, residing at 564 Dorchester street east, in the city of Montreal, Province of Quebec, Canada, have invented certain new and useful Improvements in Bathing-Shoes; and I do hereby declare that the following is a full, clear, and exact description of the invention, such as will enable others skilled in the art to which it appertains to make and use the same.

10 The invention to be hereinafter described relates to bathing shoes.

15 In order to more clearly disclose the construction, operation, and use of the invention, reference should be had to the accompanying drawings forming part of the present application.

20 Throughout the several figures of the drawings like reference characters designate the same parts.

25 In the drawings: Figure 1 is a side view of the shoe; and Fig. 2 is a longitudinal, vertical sectional view.

30 The main objects of this invention are; to provide a bathing shoe which will protect the foot of the wearer, as well as prevent sand, gravel, or other foreign matter from entering the shoe; which will be neat in appearance; and which may be easily and cheaply manufactured.

35 The shoe is molded of one continuous piece of soft rubber. The bottom of the shoe is made much thicker than the body 1 so as to form a sole 2. It should be noted that the sole 2 is inside of the shoe and integral with the body 1. By this means the expense attendant upon making an independent sole and attaching it to the body 1 is dispensed with. Also, the sole being molded integral with the body 1 the bottom of the shoe is absolutely water tight. By having the sole inside of the shoe the 40 shoe is given a very neat appearance; also there is no possibility of sand or gravel being picked up on the upper surface of the sole while walking or bathing, as in the ordinary shoe. The sole 2 being of thick

rubber effectually protects the foot of the 50 bather, while at the same time producing a cushioning effect which greatly diminishes the jar of walking and thus prevents the bather from tiring as quickly as if wearing the ordinary bathing shoe. 55

The leg portion 3 of the shoe is turned inwardly as at 4 to form an elliptical opening 5.

55 In putting the shoe on, the foot is inserted through the opening 5 and the shoe 60 drawn upon the foot so that the turned over portion 4 comes well above the ankle. In this position, the upper part of the shoe, owing to its being turned in and reduced, fits snugly about the leg of the wearer and 65 effectually prevents the entry of sand, gravel, or other foreign matter into the shoe. As it is turned over at the top, the shoe 70 will not grip the leg of the wearer tightly enough to cause discomfort, as the turn will permit a slight give and thus create a cushioning effect of the gripping portion.

75 It is thought that the construction, operation, and use of the invention will be clear from the preceding detailed description.

Changes may be made in the construction, arrangement, and disposition of the several parts of the invention without in any way departing from the field and scope of the 80 same, and it is meant to include all such within this application wherein only a preferred form has been disclosed.

Having thus fully described by invention, what I claim as new and desire to secure by 85 Letters Patent is:

1. A bathing shoe molded of one piece of gum or india rubber and having its bottom made much thicker than the body of the shoe so as to form a sole integral therewith and contained therein, and having the upper end of the leg portion turned inwardly to form means for closely gripping the leg of the wearer. 90

2. A bathing shoe formed exclusively of 95 soft flexible elastic sand tight material adapted to conform to and completely inclose the entire foot in a snug glove-like

sand tight fit, and means for maintaining a snug sand tight closure between the upper open end and the leg of the wearer.

3. A bathing shoe formed exclusively of 5 soft flexible elastic sand tight material adapted to conform to and completely inclose the entire foot in a snug glove-like sand tight fit, and flexible elastic means for maintaining a snug sand tight closure be-

tween the upper open end and the leg of 10 the wearer.

In witness whereof I have hereunto set my hand in the presence of two witnesses.

ALBERT AUMONT.
